COMBINATION CAPPING AND PACKING DEVICE

Filed Nov. 26, 1928

UNITED STATES PATENT OFFICE

CLAUD HARRY BARRETT, OF LONG BEACH, CALIFORNIA

COMBINATION CAPPING AND PACKING DEVICE

Application filed November 26, 1928. Serial No. 321,825.

This invention relates to a combination capping and packing device by means of which an oil or gas well may be effectively prevented from flowing in event that it should 5 be out of control, such as when a well comes in while drilling or before the crew are entirely prepared to cope with unusual conditions which might suddenly arise due to extremely high gas pressure, or the like.

10 An object of my invention is to provide a device of the character stated which can be placed around the well casing, and said casing may then be cut and a plate or packing inserted to stop the flow of the well.

15 Another object is to provide a combination capping and packing device from which the well may be produced as it is capped and the further object of safe-guarding the workers during the casing cutting operation.

20 Other objects, advantages, and features of invention may appear from the accompanying drawings, the subjoined detailed description, and the appended claims.

In the drawings

25 Figure 1 is a side elevation partly in section of my device showing the casing cut and the stop in position.

Figure 2 is a fragmentary side elevation with parts broken away to show interior construction and illustrating the cutting element in position after cutting the casing.

30 Figure 3 is an enlarged fragmentary half sectional view of the feed arrangement.

Figure 4 is a sectional view taken on line 4, 4 of Figure 1.

Figure 5 is a plan view of the cutting carriage.

Figure 6 is a side elevation, partly in section, of my packing device with the packer in position.

Figure 7 is a longitudinal sectional view of the packer placing cartridge.

Figure 8 is a plan view of the same.

45 Figure 9 is an enlarged fragmentary view of the expandible plates 24 shown in Figure 7.

Referring more particularly to the drawings, the numeral 1 indicates the bowl of my 50 capping and packing device which is made

in two sections 2, 3 which sections are adapted to be placed around the casing 4 and securely bolted in position in the usual and well-known manner. An opening 5 is provided in one side of the member 3 and a gate valve 6 is mounted over this opening. A pipe 7 extends from the valve 6 and a second valve 8 is positioned at the forward end of said pipe. The valves 6, 8 are of usual and well-known construction and the details of these valves form no part of this invention.

A reducing nipple 9 is secured to the valve 8 and a threaded sleeve 10 of any desired length screws into the forward end of the nipple. A packing gland 11 is formed in the sleeve 10 and fits closely about the shaft 12 to prevent leakage around the shaft. The shaft 12 terminates at its inner end in a cutter 13 and the shaft is journaled in a carriage 14. This carriage is adapted to slide in groove-ways 15 which are formed in the pipe 7 and the bowl 1. This shaft is rotated by any suitable source of power (not shown). An outlet valve 16 is mounted on the member 2 and this valve may be opened as the well 70 is capped so as to permit the well to flow therethrough.

When it is desired to cap the well the parts are arranged as shown in Figures 1 and 2 with the valves 16 and 6 closed. The valve 8 is open and upon removing the nipple 9 the carriage 14 and cutter 13 are moved into the pipe 7. The nipple 9 is now mounted in position and the valve 6 is opened. The cutter is advanced until it contacts with the casing 4, after which the shaft 12 is rotated and gradually advanced through the sleeve 10 until the cutter has severed the casing. When the casing has been cut the carriage 14 is pulled outwardly, the valve 6 is again closed and the carriage is removed from the pipe 7.

A plate 17 is now pushed into the pipe 7 in the groove-ways 15. A bar (not shown) corresponding to the shaft 12 bears against the plate 17 and when the valve 6 is now opened this plate can be shoved into the bowl 1, as shown in Figure 1, thus effectively stopping the flow through the casing. The valve 6 is then closed and this valve fits

against the plate 17, thus securely holding it in position. Now if desired, the valve 16 may be opened and the well can continue to flow under proper supervision.

At times it is not desirable to cap the well as previously described or perhaps it is not possible to do this because of the presence of drilling tools in the casing. For this contingency I provide a packing means as follows: A bowl 18 is secured around the casing in the same manner as previously described and the bowl is provided with valves 19, 20 corresponding to the valves previously described. The pipe 21 extends from the valve 19 and is provided with groove-ways 22 as previously described.

A cartridge 23 is adapted to be pushed into the pipe in the same manner as the plate 17 and within this cartridge I position a pair of expandible plates 24 which plates are secured to a cable 25. The two plates are pivotally secured together at the top thereof as shown at 24'. The lower end of the cable is provided with a loop 26 which is adapted to fit over a hook 27 in the bowl 18. The plates, cable, and loop are preferably positioned, as shown in Figure 7, so that as the cartridge is advanced in the pipe 21 the loop will engage the hook and be held thereby. The cable is of steel and stiff enough to remain bent in the position to engage the hook 27. A notch 27' is provided in the front edge of the cartridge 23 to prevent the loop 26 from slipping sideways.

35 A spring 28 is positioned in the cartridge and bears against the plates, the spring being held compressed by a trigger 29 mounted on top of the cartridge. The trigger 29 is engaged and depressed by the cam 30, thus 40 releasing the plates and the spring 28 forces them outwardly into the casing. The pressure in the well forces the plates upwardly and expands them against the sides of the casing, as shown in Figure 6, after which 45 packing may be fed through the pipe. The packing lodges against the plates 24 and effectively seals the well. The plates 24 in themselves are not sufficient to entirely shut off the well, but they act as a stop for packing 50 which is subsequently fed against the plates.

Having described my invention, I claim:

1. A combination capping and packing device for an oil well casing comprising a bowl adapted to be mounted around the well 55 casing, a valve secured to the bowl, a pipe extending from the valve, said pipe and bowl having groove-ways formed therein, a cartridge adapted to fit into the groove-ways, expandible plates mounted in the cartridge, a cable secured to the plates, and a hook upon which the cable is adapted to be secured when the plates are carried upwardly in the casing.

60 2. A combination capping and packing device for an oil well casing comprising a bowl

adapted to be mounted around the well casing, a valve secured to the bowl, a pipe extending from the valve, said pipe and bowl having groove-ways formed therein, a cartridge adapted to fit into the groove-ways, 70 expandible plates mounted in the cartridge, a cable secured to the plates, and a hook upon which the cable is adapted to be secured when the plates are carried upwardly in the casing, 75 spring means in the cartridge, and means to trip said spring means whereby the plates are forced into the casing.

In testimony whereof, I affix my signature.

CLAUD HARRY BARRETT.
